UNITED STATES PATENT OFFICE.

SAMUEL M. SMITH, OF CHICAGO, ILLINOIS.

SOIL-PIPE FITTING.

1,081,683.

Specification of Letters Patent. Patented Dec. 16, 1913.

Application filed June 3, 1912. Serial No. 701,317.

To all whom it may concern:

Be it known that I, SAMUEL M. SMITH, a citizen of the United States, and a resident of the city of Chicago, county of Cook, 5 and State of Illinois, have invented certain new and useful Improvements in Soil-Pipe Fittings, of which the following is a specification.

My invention relates to improvements in 10 soil pipe fittings for the use of plumbers, and has for its object the provision of a fitting of this character of improved construction and operation.

The invention consists in the combinations 15 and arrangements of parts hereinafter described and claimed.

The invention will be best understood by reference to the accompanying drawings forming a part of this specification, and in 20 which—

Figure 1 is a diagrammatic plan view showing a fitting embodying my invention as in position for use, Fig. 2, an enlarged side elevation of a fitting in position of use, and Fig. 25 3, an enlarged top plan view of a fitting in position of use.

The preferred form of construction, as 30 illustrated in the drawings, comprises a hollow casing 1 having alining hubs or nipples 2 and 3 at one end and adapted to receive soil pipe sections 4, as will be readily understood by those skilled in the art. Casing 1 is also provided with upwardly extending hubs or nipples 5 and 6 which are adapted 35 to receive the lower ends of vent pipes 7, as shown. Supporting recesses 8 are formed in the upper central portion of casing 1 between nipples 2 and 5, and 5 and 6 and are adapted to receive supporting rails 9. These 40 supporting rails 9 are made of a length to span two adjoining joists 10 in the floor of a building, and are connected by means of a bridge 11 which is arranged nearer one end of said supporting rails than the other, or 45 in a non-central position. By this arrangement of bridge 11, the supporting rails will be firmly held together and may be inserted in recesses 8 no matter what position the fitting may occupy between the joists 10.

50 At its end opposite nipples 2 and 3 and adjacent its top, casing 1 is provided with an outwardly inclined nipple or hub 12 which is arranged at substantially thirty degrees to the side of said casing, as shown.

55 A smaller nipple 13 is arranged in the side

of casing 1 between nipple 12 and nipples 2 and 3 and at an elevation slightly higher than nipple 12. Nipple 12 is adapted to receive a waste pipe 14 from an ordinary water-closet bowl 15, and nipple 13 is adapted to receive a waste pipe 16 from a bath tub 17. At its outer end casing 1 is provided with an upwardly and outwardly inclined elongated nipple 18 which is adapted to receive a waste pipe 19 leading from a washbowl 20. Nipple 18 is extended upwardly sufficiently to pass above the floor supported by joists 10 so as to facilitate access to said nipple and obviate the necessity of tearing up a floor to give access to said 70 nipple. By this arrangement of nipples, it will be observed that the various fixtures in a bath room will readily waste or drain without danger of inducing siphonic action in any of the others, and that said fixtures 75 may be conveniently and expeditiously arranged in the bath room with the water-closet bowl between the washbowl and bath tub, as indicated in Fig. 1, this arrangement being highly desirable in small bath rooms. 80

When the fitting is inserted in the partition of a bath room, as is frequently done, a T 22 may be inserted in pipe 19 and serve as a means of connection with a sink or other fixture located on the other side of the 85 partition, as indicated diagrammatically in Fig. 1.

While I have illustrated and described the preferred form of construction for carrying my invention into effect, this is capable of 90 variation and modification without departing from the spirit of the invention. I, therefore do not wish to be limited to the exact details of construction set forth, but desire to avail myself of such variations and 95 modifications as come within the scope of the appended claim.

Having described my invention, what I claim as new and desire to secure by Letters Patent, is:

As an article of manufacture, a fitting of the class described, comprising a hollow casing having an upwardly inclined bottom and a horizontal top, the top being provided with a series of hubs to receive pipe ends 105 and the bottom at its lowermost end being provided with an opening in alinement with the corresponding end hub in the top, reduced necks connecting said hubs and said casing forming recesses to receive support- 110

ing members, there being hubs in the side wall of said casing and the smaller end of said casing terminating in an upwardly and outwardly inclined neck extending beyond 5 the casing proper and terminating in a substantially horizontal position above the level of said necks, substantially as described.

In testimony whereof I have signed my name to this specification in the presence of two subscribing witnesses.

SAMUEL M. SMITH.
